CLAIM

We claim the ornamental design for a plunger and finger grip for a hypodermic syringe, as shown and described.

DESCRIPTION

FIG. 1 is a front elevation view of a hypodermic syringe; FIG. 2 is a side elevation view of the hypodermic syringe of FIG. 1;

FIG. 3 is a perspective view of the hypodermic syringe of FIG. 1;

FIG. 4 is a top plan view of the components of the embodiment shown in FIGS. 1-3 of the hypodermic syringe;

FIG. 5 is a perspective view of an alternate configuration of the hypodermic syringe of FIG. 1; and,

FIG. 6 is perspective view of another alternate configuration of the hypodermic syringe of FIG. 1.

The features shown in broken lines depict environmental subject matter only and form no part of the claimed design.
